UNITED STATES PATENT OFFICE

150,809

DESIGN FOR A STAPLING DEVICE

Richard E. Powers, Los Angeles, Calif., assignor
to Powers Manufacturing Company, Los Angeles, Calif., a firm composed of Richard E. Powers, Merel E. Powers, and Robert J. Miller

Application October 12, 1946, Serial No. 133,904

Term of patent 14 years

(Cl. D74—1)

To all whom it may concern:

Be it known that I, Richard E. Powers, a citizen of the United States, residing at Los Angeles, in the county of Los Angeles and State of California, have invented a new, original, and ornamental Design for a Stapling Device, of which the following is a specification, reference being had to the accompanying drawing, forming part thereof, the single figure of which is a perspective view of a stapling device embodying my new design.

I claim:

The ornamental design for a stapling device, substantially as shown.

RICHARD E. POWERS.
